CAKE DECORATION

Charles Fischett, South Ozone Park, N.Y.

Application April 29, 1958, Serial No. 50,660

Term of patent 14 years

(Cl. D8—1)

FIG. 1

FIG. 2

Fig. 1 is a front view of a cake decoration, showing my new design; and

Fig. 2 is a sectional view thereof taken on line 2—2 of Fig. 1.

I claim:

The ornamental design for a cake decoration, as shown.
